PROCESS FOR THE PRODUCTION OF ALKYL
DIARYL ESTERS OF ORO-PHOSPHORIC
ACIDHarry R. Gamrath, St. Louis, Mo., assignor to
Monsanto Chemical Company, St. Louis, Mo.,
a corporation of DelawareNo Drawing. Application February 7, 1949,
Serial No. 75,098

13 Claims. (Cl. 260—461)

1

This invention relates to a new method of manufacture of esters of ortho-phosphoric acid; more particularly it relates to an improved commercially feasible process for the production of certain monoalkyl diaryl phosphate esters of the general formula:

wherein R_1 represent an alkyl radical terminating with a CH_2 group and containing at least 6 and not more than 18 carbon atoms or beta-alkoxyethyl radical wherein the alkyl substituent is an alkyl group of at least 4 and not more than 18 carbon atoms and R_2 represents a phenyl, cresyl, or chlorophenyl radical. Herein when the phrase "monoalkyl diaryl phosphate ester" is used, it is the intention that the phrase include only such compounds as fall within the above definition.

This application is a continuation-in-part of copending application Serial No. 38,194, filed July 12, 1948, now abandoned, which is a continuation-in-part of application Serial No. 720,310, filed January 4, 1947, now abandoned.

The monoalkyl diaryl phosphate esters prepared by the novel process of this invention are generally nearly colorless liquids having mild pleasant odors. These esters have exceptional utility as flexibilizing plasticizers for polyvinyl chloride compositions, imparting to those compositions the combination of properties of flexibility at freezing temperatures, low volatility losses of plasticizer at higher temperature and non-inflammability. Because of their very low pour points and very high autoogenous ignition temperatures and their compatibility with paraffinic hydrocarbon oils, these monoalkyl diaryl phosphates may be used alone or in combination with paraffinic hydrocarbon oils to prepare hydraulic and torque converter fluids of highly desirable characteristics. Moreover, these esters have a wide variety of other uses, such as lubricants for mechanisms from delicate clock works to extreme pressure bearing surfaces, film-forming addition agents in hydrocarbon oils for use in extreme pressure lubricants and as a liquid medium for filters for air conditioning systems.

In all of the above mentioned uses of the monoalkyl diaryl phosphate esters prepared by the novel process of this invention, it is to be empha-

sized that exceptional purity is required. For example, in their use as plasticizers for polyvinyl chloride, excessive quantities of the dialkyl derivatives decrease the permanence of the plasticizer in the plasticized composition. Excessive quantities of the triaryl derivative in such application cause a decrease in the flexibility characteristics of the plasticized composition. Moreover, such impurities cause substantial changes in the autoogenous ignition temperatures of the monoalkyl diaryl phosphate esters and also substantial changes in the viscosity of the esters thereby seriously affecting the utility of these esters as hydraulic and torque converter fluids.

Various methods are known for the production of esters of phosphoric acid, however, none of these methods or processes as described in the art have proven to be commercially feasible for the production of monoalkyl diaryl phosphate esters of high purity. Furthermore, it has been found that several of these methods described in the art while possessing utility in the preparation of certain types of esters of phosphoric acid do not lend themselves to the production of monoalkyl diaryl phosphate esters.

A common procedure described is that of reacting 2 mols of phenol or similar hydroxy aryl compound with 1 mol of phosphorus oxychloride, removing the HCl formed under vacuum, and then reacting the diphenyl phosphoryl chloride with 1 mol of an aliphatic alcohol. This procedure is objectionable as the reaction is difficult to control and excessive quantities of the triaryl derivatives are formed, resulting in an impure product with low yields. Another procedure described is that of preparing the triaryl phosphates, removing one aryl group by alkaline hydrolysis followed by steam distillation and then introducing the alkyl group. The principal objectionable feature of this process is that it is exceedingly costly in view of the increased number of steps required to produce the finished product. A further method described is that of reacting in excess of 1 mol of an aliphatic alcohol with 1 mol of phosphorus oxychloride, removing the HCl formed under vacuum, purifying the monoalkyl phosphoryl dichloride by distillation and subsequently reacting at a relatively high temperature the purified acid chloride with 2 mols of phenol or similar hydroxy aryl compound. According to

this latter process, in order to obtain pure neutral phosphate esters, it is essential that the intermediate alkyl phosphoryl dichloride be separated from the reaction mixture and purified. This is accomplished by fractional distillation of the acid chloride from the reaction mass. Pure esters may also be obtained by fractionating the crude neutral phosphate esters. This process has given satisfactory results when the aliphatic alcohol used was a primary alcohol of relatively short chain length. However, it is known that secondary, tertiary, and substituted alcohols are not suited to this reaction. Typical alcohols which do not satisfactorily undergo the reaction as described are the allyl or substituted allyl alcohols, nitro alcohols, secondary butyl alcohol, benzyl alcohol and 2-octanol. Moreover, it has been found that monoalkyl phosphoryl dichlorides tend to decompose with such decomposition being dependent upon time and temperature. In the case of the lower alkyl phosphoryl dichlorides, such as the C₁-C₄ alkyl phosphoryl dichlorides, the boiling points of the compositions are lower than their respective decomposition temperature range under commercially practical subatmospheric pressure thereby permitting purification of the monoalkyl phosphoryl dichloride by fractionation. However, the decomposition temperature ranges of the monoalkyl phosphoryl dichlorides which are intermediate to the formation of the monoalkyl diaryl phosphate esters prepared by the novel process of this invention are lower than their respective boiling points that could be obtained under commercially feasible subatmospheric pressures, thus rendering purification of the intermediate monoalkyl phosphoryl dichlorides by commercial fractionation impossible. Furthermore, if purified intermediate alkyl phosphoryl dichlorides are obtained and subsequently reacted with hydroxy aryl compounds to form monoalkyl diaryl phosphates, the relatively high temperatures required to cause the reaction to proceed essentially quantitatively are again higher than the decomposition temperature ranges of the respective alkyl phosphoryl dichlorides and consequently decomposition again results.

Typical relationships that exist between the boiling point and the decomposition temperature range of various alkyl phosphoryl dichlorides are shown on the following table wherein:

Column A is the time required for the exothermic decomposition to start when the alkyl phosphoryl dichloride is maintained at 100°-110° C.

Column B is the boiling range when the mass temperature is maintained at 70-80° C., which is a reasonably safe mass temperature in view of the exothermic decomposition characteristics.

It is evident that methyl phosphoryl dichloride may be purified by fractionation inasmuch as no decomposition was found after 24 hours at 100°-110° C. and that its boiling point under 30 mm. vacuum, a commercially feasible pressure, is below its decomposition point. Butyl phosphoryl dichloride and isoamyl phosphoryl dichloride may similarly be fractionated as their boiling points at commercially feasible subatmospheric pressures may be reduced below their respective decomposition temperature ranges. However, it is evident that as the length of the alkyl chain is increased the tendency to decompose is also increased which is substantiated by considering the other mentioned alkyl phosphoryl dichlorides. Thus it is evident from the extremely short decomposition time of the isoamyl phosphoryl chloride at 100°-110° C. and the high vacuum necessary to reduce its boiling point so that it may be fractionated without decomposition, that a further increase in the length of the alkyl chain would render impossible purification of the alkyl phosphoryl dichloride by distillation. Considering the alkyl phosphoryl dichlorides which are intermediate to the formation of the monoalkyl diaryl phosphates prepared by the novel process of this invention, it is seen that commercial purification of these acid chlorides by fractionation is impossible. Before the boiling points of these materials could be reached, decomposition would have resulted as evidenced by the exothermic decomposition reaction and separation of the decomposition products into two distinct layers. In order to distill these materials, a vacuum higher than that could be obtained with commercially practical equipment would be necessary. Molecular distillation has also proven to be unsatisfactory for the purification of these alkyl phosphoryl dichlorides because of their highly corrosive nature and their tendency to "gas."

Butoxyethyl phosphoryl dichloride does not decompose in essentially the same manner as do the other derivatives, that is, an exothermic decomposition accompanied with a separation of the decomposition products, but on being subjected to heat, the butoxyethyl phosphoryl dichloride severely discolors, which coloration is evident in the final butoxyethyl diphenyl phosphate. Thus, according to the methods heretofore practiced, the elevated temperatures used in the reaction of alkoxyethyl phosphoryl dichlorides with a hydroxy aryl compound would lead to highly colored monoalkoxyethyl diaryl phosphate esters which are not suitable for the applications previously mentioned.

In view of the teachings of the art, one would not believe commercial production of essentially pure monoalkyl diaryl phosphate esters would be economically practical or feasible. First, con-

Compound	Specific Gravity 25/26° C.	A	B
Methyl phosphoryl dichloride.....	1.4890	None in 24 hours.....	62-65°/30 mm.

sidering the general resistance of secondary, tertiary or substituted alcohols to the formation of the corresponding alkyl phosphoryl dichloride, it would not be expected that highly branched C_8 to C_{18} alcohols or alkoxyethyl alcohols wherein the alkyl substituent consists of an alkyl group of at least 4 and not more than 18 carbon atoms, would satisfactorily react with phosphorus oxychloride to form the monoalkyl phosphoryl dichloride. Secondly, in view of the teachings of the art, those monoalkyl phosphoryl dichlorides which could be prepared, could be formed only in limited quantities by reacting a considerable molar excess of the alcohol with phosphorus oxychloride. However, inasmuch as a pure alkyl phosphoryl dichloride is necessary to permit the production of a pure monoalkyl diaryl phosphate, the alkyl phosphoryl dichloride would have to be purified by fractionation before subsequent reaction with a hydroxy aryl compound and as previously pointed out in view of the decomposition characteristics of these alkyl phosphoryl dichlorides purification by fractionation would be impossible. Similarly any attempt at a quantitative reaction between a purified monoalkyl phosphoryl dichloride and a hydroxy aryl compound would also result in failure due to the high temperature necessary to cause the reaction to approach quantitative values also being higher than the decomposition temperature range of the acid chloride thereby causing decomposition of the reaction mass. Furthermore, it is obvious that the methods as heretofore practiced would yield esters containing considerable quantities of impurities which would necessitate purification by fractionation of the esters in order to obtain organic phosphate esters of sufficient purity for utility in the applications discussed herein.

It is an object of this invention to provide an improved process for the production of monoalkyl diaryl phosphate esters.

It is a further object of this invention to provide an improved commercially feasible process for the production of high purity monoalkyl diaryl phosphate esters.

Moreover, it is an object of this invention to provide an improved commercially feasible process for the production of monoalkyl diaryl phosphate esters wherein the simple reactions of the process produce esters of such a high degree of purity that further purification by fractionation of the ester is unnecessary.

Still further objects will become apparent from the description of the novel process and the claims.

These objects are attained by the novel process of this invention by reacting under controlled conditions one molecular proportion of a C_8 to C_{18} primary alkyl alcohol or beta-alkoxyethyl alcohol, wherein the alkyl substituent consists of an alkyl radical of at least 4 and not more than 18 carbon atoms, with one molecular proportion of phosphorus oxychloride, while continuously removing the HCl formed under vacuum, thereby forming in essentially quantitative yields, requiring no further purification, the monoalkyl phosphoryl dichloride. This organic phosphoryl dichloride is then added under controlled conditions to substantially two molecular proportions of sodium arylate in an aqueous solution. The resultant monoalkyl diaryl phosphate thus formed in high yields is separated from the aqueous reaction mass, washed with water and dilute alkali and dehydrated under vacuum. The ester thus obtained is of such a high degree of purity that

further purification by fractionation is unnecessary.

The high degree of purity of the esters obtained is illustrated by the following elemental analysis of esters obtained by the novel process of this invention.

Compound	O	H	P
2-ethylketyl diphenyl phosphate (Product of Example I)	Per cent	Per cent	Per cent
Calculated for: $C_{18}H_{20}O_4P$	66.31	7.46	8.57

Found.....			

20 The monoalkyl diaryl phosphate esters that may be prepared by the novel process of this invention are illustrated by the following compounds, although it is not intended that this invention be limited solely to the preparation of these compounds.

- 2-ethylbutyl diphenyl phosphate
2-methylpentyl dicresyl phosphate
Octyl dicresyl phosphate
2-ethylhexyl dicresyl phosphate
2-ethylhexyl di-p-cresyl phosphate
Iso-octyl dicresyl phosphate
Iso-octyl di-p-cresyl phosphate
2-ethylhexyl diphenyl phosphate
Octyl diphenyl phosphate
Iso-octyl diphenyl phosphate
Nonyl diphenyl phosphate
Trimethylhexyl diphenyl phosphate
Nonyl dicresyl phosphate
Decyl dicresyl phosphate
Dodecyl diphenyl phosphate
Dodecyl dicresyl phosphate
2-n-propylheptyl diphenyl phosphate
Hexoxyethyl diphenyl phosphate
Butoxyethyl diphenyl phosphate
2-ethylbutoxyethyl dicresyl phosphate
2-methylpentoxyethyl diphenyl phosphate
n-Hexaoxyethyl dicresyl phosphate
2-methylpentoxyethyl dicresyl phosphate
Octoxyethyl dicresyl phosphate
2-ethylhexoxyethyl diphenyl phosphate
Iso-octoxyethyl dicresyl phosphate
2-ethylhexoxyethyl dicresyl phosphate
n-Octoxyethyl diphenyl phosphate
Nonoxyethyl dicresyl phosphate
Trimethylhexoxyethyl diphenyl phosphate
n-Decoxyethyl dicresyl phosphate
2-n-propylheptoxyethyl dicresyl phosphate
Decoxyethyl diphenyl phosphate
2-n-propylheptoxyethyl diphenyl phosphate
Dodecoxyethyl diphenyl phosphate
Dodecoxyethyl dicresyl phosphate
Butoxyethyl di-m-cresyl phosphate
2-ethylhexoxyethyl di-m-cresyl phosphate
Butoxyethyl di(o-chlorophenyl) phosphate
2-methylpentyl di(o-chlorophenyl) phosphate
2-ethylhexyl di(o-chlorophenyl) phosphate
2-n-propylheptyl di(o-chlorophenyl) phosphate
Dodecyl di(o-chlorophenyl) phosphate
Tridecyl diphenyl phosphate
Tridecyl di-m-cresyl phosphate
Tridecoxyethyl diphenyl phosphate
Tetradecyl di(o-chlorophenyl) phosphate
Tetradecyl di p-cresyl phosphate
75 Tetradecoxyethyl diphenyl phosphate

- Pentadecyl dicresyl phosphate
 Pentadecyl diphenyl phosphate
 Pentadecoxyethyl di(p - chlorophenyl) phosphate
 Hexadecyl diphenyl phosphate
 Hexadecyl di-m-cresyl phosphate
 Hexadecoxyethyl di(o-chlorophenyl) phosphate
 Heptadecyl diphenyl phosphate
 Heptadecyl di-o-cresyl phosphate
 Heptadecoxyethyl diphenyl phosphate
 Octadecyl di(o-chlorophenyl) phosphate
 Octadecyl di(o-chlorophenyl) phosphate
 Octadecoxyethyl dicresyl phosphate

In the above list of compounds, the nonyl and dodecyl radicals may be derived, in addition to the conventional sources, from the polymerization products of olefins, such as propylene, or the dodecyl radical may be derived from the polymerization products of olefins such as butylene. These alkyl radicals may also be derived from branched chain primary alcohols prepared by the polymerization of olefins to form a branched chain olefin, followed by the reaction with carbon monoxide and hydrogen (oxo process) to form a primary branched chain alkyl alcohol. Thus a nonyl alcohol may be prepared from the polymerization of isobutylene to form an octene which may then be reacted with carbon monoxide and hydrogen to form a branched chain primary nonyl alcohol. Nonaldehyde may be prepared in a similar manner and may then be subjected to an aldol condensation to form a branched chain primary octadecyl alcohol. The alkyl radicals may also be derived from straight chain primary alcohols obtained by the hydrogenation of coconut oil and fats.

In the monoalkyl dicresyl phosphates which are intended to be prepared by the novel process of this invention, the cresyl radical may be an ortho-cresyl, para-cresyl, or meta-cresyl. Similarly in those compounds containing a chlorinated phenyl radical, the chlorophenyl radical may be an ortho-chlorophenyl, para-chlorophenyl, or meta-chlorophenyl radical.

EXAMPLE I

2-ethylhexyl diphenyl phosphate

Forty-six grams of POCl_3 are cooled with stirring to about 15° C. in a glass lined closed reaction vessel. Thirty-nine grams of 2-ethylhexanol which have been cooled to approximately 15° C. are added to the POCl_3 with continuous stirring and at a rate so as to maintain a reaction-mass temperature of about 15° C. The reaction mixture is agitated and the reaction temperature of 15° C. is maintained for one hour following the addition of all the 2-ethylhexanol, thereafter the temperature is allowed to rise to 25° C. and the stirring continued for another hour. The hydrogen chloride gas which is evolved from the reaction is continuously removed by means of applying a vacuum to the reaction vessel. After the reaction between the 2-ethylhexanol and the POCl_3 and the removal of the hydrogen chloride have been completed, the substantially pure 2-ethylhexyl phosphoryl dichloride is transferred to a reactor containing 250 g. of an aqueous solution, cooled to 0° C., having a composition of 32% sodium phenate. The 2-ethylhexyl phosphoryl dichloride is added to the aqueous sodium phenate solution at such a rate as to maintain a temperature below 5° C. After all the 2-ethylhexyl phosphoryl dichloride has been added to the aqueous sodium phenate solution, the reaction mix-

ture is agitated for an hour and then, with continuous stirring, allowed to warm up to room temperature. The mixture is then allowed to stand until an ester layer and an aqueous layer form; the ester layer is then separated from the aqueous layer. The ester is given successive washes with 2% NaOH solution and water and then dehydrated under vacuum at about 100° C. The yield, based on POCl_3 , was 91%.

10 The 2-ethylhexyl diphenyl phosphate prepared in the above manner had the following properties:

Sp. gr. 25/25° C.	1.090
N_D^{25}	1.510
Boiling point at 5 mm.	Approx. 232° C.
Freezing point	Below 0° C.
Color	Nearly water white
Pour point	-65° C.
20 Viscosity -30° F.	2167 centistokes
Viscosity 100° F.	10.1 centistokes
Viscosity 210° F.	2.46 centistokes
Autogenous ignition temperature	10.50° F.

25 While specific quantities, temperatures and reaction conditions have been set forth in Example I, it is not intended that the novel process of this invention be restricted solely thereto as to a certain degree these quantities, temperatures and reaction conditions may be varied. Thus, in the first step of the reaction, that is the formation of alkyl phosphoryl dichloride, it is preferred that substantially one molecular proportion of the aliphatic alcohol be used for each one molecular proportion of phosphorus oxychloride. A slight variation is permissible however as the molecular proportion of the alcohol is increased beyond the preferred one molecular proportion, the formation of dialkyl phosphoryl chloride is pro-

30 moted affecting the yield and quality of the final product. If the molecular proportion of the alcohol is reduced below the preferred one molecular proportion, the yield of the finished product is reduced due to the presence of unreacted phosphorus oxychloride which must be removed by fractionation to prevent the formation of the tri-aryl derivative during the subsequent reaction.

The reaction between the alcohol and the phosphorus oxychloride is exothermic and is accompanied by a considerable evolution of hydrogen chloride. The rate of addition of the alcohol and the temperature at which the reaction mass is maintained is therefore governed by the nature of the equipment, cooling capacity and ability to remove hydrogen chloride as it is formed to prevent too violent a reaction. While it is preferred that the addition rate be so governed that the temperature may be maintained at substantially 15° C. it is evident that such a rate of addition and temperature will depend to a large extent on the nature of the equipment used and ability to control temperature to prevent loss of the reactants through volatilization.

The practical temperature range limits of this reaction are also governed by the freezing point of POCl_3 and the color of finished product desired. Since POCl_3 crystallizes at approximately 2° C., initial reaction temperatures below 2° C. are not practical. Once the reaction is begun, the

55 temperature may then be reduced below +2° C. as the alcohol added and the alkyl phosphoryl dichloride formed depress the crystallizing point of the mass so that lower temperatures may be maintained. As the temperature of the reaction is increased greater than 25° C., the color of the

60

65

70

monoalkyl phosphoryl dichloride is increased resulting in more highly colored monoalkyl diaryl phosphate esters. Thus, the preferred and practical temperature range of this reaction is from about 2° C. to about 25° C. After the reaction is substantially complete, the temperature may be increased to a maximum of 50° C. to facilitate the removal of the hydrogen chloride gas evolved in the reaction.

It is also preferred that the alcohol be added to the POCl_3 . While the reverse order of addition of reactants may be utilized, such a reverse order promotes the formation of the dialkyl phosphoryl chloride and trialkyl phosphate ester thereby affecting the purity of the final product.

The concentration of the sodium arylate solution is governed by the solubility of the sodium arylate at the temperature at which the reaction between the alkyl phosphoryl dichloride and sodium arylate is carried out. It is obvious that the concentration of the sodium arylate solution should approach the solubility limit of sodium arylate at the reaction temperature for economic and production reasons. However, it is also obvious that significantly lower concentrations may be used if desired.

It is preferred that two molecular proportions of sodium arylate be used for each one molecular proportion of alkyl phosphoryl dichloride with a maximum of 5% excess. If less than two molecular proportions of sodium arylate be used, the yield of the final product will be reduced. If greater than a 5% excess is used, purification of the final product will be made more difficult in that excessive quantities of sodium arylate will have to be removed from the final product.

The temperature of the reaction between the sodium arylate and the monoalkyl phosphoryl dichloride is preferably between 0° and 25° C., however the reaction may be carried out from -10° to substantially 50° C. If the temperature of the reaction is maintained at the higher level, however, the color of the final product is somewhat darker than that that would have resulted if the reaction had been carried out at 0° to 25° C. Maintaining a reaction temperature of less than 0° C. limits the concentration of the sodium arylate solution that may be utilized.

In carrying out the reaction between the monoalkyl phosphoryl dichloride and sodium arylate it is highly preferred that the monoalkyl phosphoryl dichloride be added to the sodium arylate solution in order to obtain a pure monoalkyl diaryl phosphate ester. Reversing the order of addition of the reactants invariably leads to hydrolysis with subsequent low yields of the finished product and the formation of a considerable amount of impurities.

The esters prepared by the novel process of this invention are of such a degree of purity, as heretofore mentioned, that purification by fractionation is unnecessary. Usually all that is required is a simple water and alkali wash followed by dehydration under vacuum. At times, however, it may be necessary to subject some of the more difficultly purified esters to a simple steaming procedure to remove the last traces of the alcohol or other volatiles. This steaming operation can then be followed by dehydration in the normal manner.

If the alkyl phosphoryl dichloride is added to the sodium arylate at temperatures below 10° C., the resulting phosphate ester is usually substantially colorless. However, the phosphate esters with more color may be treated by the conven-

tional means well known to those familiar with the art to remove the undesirable color.

EXAMPLE II

Nonyl diphenyl phosphate

460.2 g. of POCl_3 are cooled with stirring to a temperature of 5 to 10° C. in a glass lined closed reaction vessel. 432.8 g. of a nonyl alcohol (a trimethyl substituted primary hexanol) are cooled to 5 to 10° C. and are added to the POCl_3 with continuous stirring at a rate so as to maintain a reaction-mass temperature of about 15° C. The reaction mixture is agitated and the temperature of the reaction mixture is allowed to come up to room temperature, thereafter the stirring is continued and the reaction mixture is placed under a vacuum (below 50 mm.) over a period of 2 hours thereby removing the hydrogen chloride gas which is evolved from the reaction.

10 An aqueous solution of sodium phenate is prepared by adding 592.2 g. of phenol to 840 cc. of water having dissolved therein 542.0 g. of 46.5% sodium hydroxide. The aqueous sodium phenate solution is cooled to 0° C. and the nonyl phosphoryl dichloride, prepared by the reaction of the nonyl alcohol and the POCl_3 , is added to the aqueous sodium phenate solution at such a rate as to maintain a temperature below 5° C. After all of the nonyl phosphoryl dichloride has been 20 added to the aqueous sodium phenate solution, the reaction mixture is agitated for a period of 3 hours and allowed to warm up to room temperature. When the agitation is stopped, the reaction mixture separates into an ester layer and an aqueous layer and the ester layer may be then separated from the aqueous layer by decantation. The ester layer is given successive washes with 2% NaOH solution and water and then dehydrated under vacuum at about 100° C. The 25 yield, based on POCl_3 , was 90%.

The nonyl diphenyl phosphate prepared as above described had the following properties:

Sp. gr. 25/25° C	-----	1.074
N_D^{25}	-----	1.505
Freezing point	-----	Below 0° C.
Color	-----	Nearly water white

EXAMPLE III

Iso-octyl diphenyl phosphate

153.4 g. of POCl_3 are cooled with stirring to about 10° C. in a glass lined closed reaction vessel. 130.2 g. of iso-octyl alcohol (6-methyl-1-heptanol) are cooled to about 10° C. and added to the POCl_3 with continuous stirring and at a rate so as to maintain a reaction temperature of 10-14° C. The reaction mixture is continuously agitated and the temperature is gradually increased to 25° C. over a period of about one hour. While the stirring is continued, the reaction mixture is placed under a vacuum (below 50 mm.) for another 1½ hours to remove the hydrogen chloride gas which is evolved from the reaction. The reaction mixture now contains 55 predominantly iso-octyl phosphoryl dichloride.

An aqueous sodium phenate solution is prepared by adding 197.5 g. of phenol to 280 cc. of water having dissolved therein 180.7 g. of 46.5% sodium hydroxide. The sodium phenate solution is cooled to about 5° C. and the iso-octyl phosphoryl dichloride is gradually added to the sodium phenate solution at such a rate as to maintain a temperature below 5° C. After all of the iso-octyl phosphoryl dichloride has been 70 added to the sodium phenate solution, the tem-

11

perature is allowed to rise to about 25° C. and the reaction mixture stirred for an additional 3 hours. When the agitation is stopped, the reaction mixture separates into an ester layer and an aqueous layer and the ester layer is then separated from the aqueous layer by decantation. The ester layer is given successive washes with 2% NaOH solution and water and then dehydrated under vacuum at about 100° C. The yield, based on POCl_3 , was 89%.

The iso-octyl diphenyl phosphate (6-methylheptyl diphenyl phosphate) prepared as above described had the following properties:

Sp. gr. 25/25° C. 1.093
 N_{D}^{25} 1.508
 Freezing point Below 0° C.
 Color Nearly water white

EXAMPLE IV

2-methylpentyl diphenyl phosphate

This ester was prepared by first reacting 102.1 g. of 2-methylpentanol with 153.4 g. of POCl_3 , in the manner as described for the preparation of 2-ethylhexyl diphenyl phosphate, to form a 2-methylpentyl phosphoryl dichloride.

The 2-methylpentyl phosphoryl dichloride was then added to a cooled solution of 440 cc. of water and 243.6 g. of sodium phenate at such a rate as to maintain a reaction temperature below 5° C. After all of the 2-methylpentyl phosphoryl dichloride had been added to the sodium phenate solution, the reaction was finished off and the 2-methylpentyl diphenyl phosphate was recovered in the same manner as was described in the preparation of 2-ethylhexyl diphenyl phosphate. The yield of 2-methylpentyl diphenyl phosphate, based on POCl_3 , was 88%, and this ester, in appearance, resembled the 2-ethylhexyl diphenyl phosphate.

EXAMPLE V

Decyl diphenyl phosphate

The decyl alcohol used in this example was a branched chain decyl alcohol manufactured from the polymerization product of olefins. While at the time of this application, the exact structure of the branched chain has not been definitely established, the fact that the alcohol does have a 10 carbon atom branched chain primary alcohol structure has been definitely established. These alcohols, generally, are manufactured by polymerizing short chain olefins to form a long chain polymeric olefinic hydrocarbon, reacting this polymer with formaldehyde and hydrogenating the polymer-formaldehyde reaction product to form the alcohol.

76.7 g. of POCl_3 were cooled with stirring to about 15° C. in a glass lined closed reaction vessel. 79.2 g. of the above described decyl alcohol were cooled and added to the POCl_3 at a rate so as to maintain a reaction temperature of about 15° C. The reaction mixture is continuously agitated and the reaction temperature is allowed to rise to room temperature, thereafter the stirring is continued and the reaction is carried to completion to form the decyl phosphoryl dichloride by placing the reaction mixture under a vacuum (below 50 mm. Hg) over a period of 2 hours, thereby removing the hydrogen chloride gas which is evolved from the reaction.

An aqueous solution of sodium phenate, prepared by adding 98.8 g. of phenol to an alkaline solution of 140 cc. of water and 89.6 g. of 46.5% sodium hydroxide, is cooled to 0° C. and the decyl phosphoryl dichloride is added to the sodium

12

phenate solution at such a rate as to maintain a reaction temperature of about 5° C. After all of the decyl phosphoryl dichloride has been added, the reaction is carried to completion, the ester recovered and purified in the same manner as was described for the preparation of 2-ethylhexyl diphenyl phosphate.

The decyl diphenyl phosphate, prepared as above described, had the following properties:

10 Sp. gr. 25/25° C. 1.068
 N_{D}^{25} 1.504
 Freezing point Below 0° C.
 Color Nearly water white

15 The yield of decyl diphenyl phosphate, based on POCl_3 , was 90%.

EXAMPLE VI

2-n-propylheptyl diphenyl phosphate

20 2-n-propylheptyl phosphoryl dichloride was prepared by reacting 79.2 g. of 2-n-propylheptanol with 76.7 g. of POCl_3 in the manner described for the preparation of decyl phosphoryl dichloride. This 2-n-propyl heptyl phosphoryl dichloride was 25 then added to 366 g. of 33.3% sodium phenate solution at a temperature of 0° C. and the reaction carried to completion, the ester recovered in the manner as described for the preparation of decyl diphenyl phosphate. The 2-n-propylheptyl diphenyl phosphate was thus prepared in a yield of 81.5% based on POCl_3 and closely resembled the decyl diphenyl phosphate prepared in the previous example.

35 **EXAMPLE VII**
 118.5 g. of a 12 carbon branched chain primary alcohol prepared from the polymerization products of olefins were cooled to about 20° C. and added to 97.8 g. of POCl_3 cooled to approximately 20° C. in a glass lined closed reaction vessel with continuous stirring and cooling so as to maintain a reaction temperature of about 20° C. 40 The reaction mixture is agitated and the temperature is slowly raised to 30 to 40° C. and maintained at that temperature for one hour following the addition of all the dodecyl alcohol; thereafter, temperature is raised to approximately 50° C. and the stirring continued for another hour. The hydrogen chloride gas which is evolved from the reaction is continuously removed by means of applying a vacuum to the reaction vessel.

45 After the reaction between the dodecyl alcohol and the POCl_3 and the removal of the hydrogen chloride has been completed the dodecyl phosphoryl dichloride is transferred to a reactor containing about 420 g. of an aqueous sodium phenate solution, at a temperature below 5° C., prepared from 180 cc. of water, 126.2 g. of phenol and 115.4 g. of 46.5% soda lye. The dodecyl phosphoryl dichloride is added to the sodium phenate solution at such a rate as to maintain a temperature below 5° C. After all the dodecyl phosphoryl dichloride has been added to the sodium phenate solution, the reaction mixture is agitated for an hour and then with continuous stirring the temperature is gradually raised to 30° C. The reaction mixture is then allowed to stand until an ester layer and an aqueous layer form and the ester layer is separated from the aqueous layer. The ester is given successive washes with NaOH solution and water and then dehydrated under vacuum at 100° C. The yield, based on POCl_3 , was 70 75 85%.

13
EXAMPLE VIII

2-ethylbutyl diphenyl phosphate

2-ethylbutyl phosphoryl dichloride was prepared by adding 51.1 g. of 2-ethylbutanol to 76.7 g. of phosphorus oxychloride, cooled to 10° C., with continuous stirring and cooling and at such a rate as to maintain a reaction temperature of 10 to 15° C. The reaction mixture is held at 15° C. for an hour following the addition of the 2-ethylbutanol and thereafter the reaction temperature is raised to 25° C. and the reaction thereafter continuously stirred and held under 30 mm. Hg vacuum (to remove the HCl evolved) for an additional hour to complete the formation of the 2-ethylbutyl phosphoryl dichloride.

The 2-ethylbutyl phosphoryl dichloride was reacted with an aqueous sodium phenate solution cooled to 0° C. and prepared by adding 98.8 g. of phenol to 140 cc. of water having dissolved therein 90.4 g. of 46.5% soda lye. The 2-ethylbutyl phosphoryl dichloride is added at a rate so as to maintain a reaction temperature below 5° C. and after all of the 2-ethylbutyl phosphoryl dichloride had been added, the reaction is finished off and the ester recovered in the manner described for the preparation of 2-ethylhexyl diphenyl phosphate. The yield of 2-ethylbutyl diphenyl phosphate, based on POCl_3 , was 89%, and the ester, in general appearance, closely resembled 2-methylpentyl diphenyl phosphate.

The 2-ethylbutyl diphenyl phosphate which was prepared in the above manner had the following properties:

Sp. gr. 25/25° C. 1.122
 N_D^{25} 1.5152

EXAMPLE IX

2-ethylhexyl dicresyl phosphate

44.3 g. of POCl_3 are cooled with stirring to about 10° C. in a glass lined closed reaction vessel. 37.6 g. of 2-ethylhexanol are cooled to approximately 15° C. and added to the POCl_3 with continuous stirring and at a rate so as to maintain a reaction temperature of about 15° C. The reaction mixture is agitated and the reaction temperature of 15° C. is maintained for one hour following the addition of all the 2-ethylhexanol, thereafter the temperature is allowed to rise to approximately 25° C. and the stirring continued for another hour. The hydrogen chloride gas which is evolved from the reaction is continuously removed by means of applying a vacuum to the reaction vessel.

After the reaction between the 2-ethylhexanol and the POCl_3 and the removal of the hydrogen chloride have been completed, the 2-ethylhexyl phosphoryl dichloride is transferred to a reactor containing 246 g. of an aqueous solution, cooled to about 0° C. having a composition of 32.1% sodium cresylate. The 2-ethylhexyl phosphoryl dichloride is added to the aqueous sodium cresylate solution at such a rate as to maintain a temperature below 5° C. After all the 2-ethylhexyl phosphoryl dichloride has been added to the aqueous sodium cresylate solution, the reaction mixture is agitated for an hour and then with continuous stirring the temperature is gradually raised to 30° C. The reaction mixture is then allowed to stand until an ester layer and an aqueous layer form and the ester layer is separated from the aqueous layer. The ester is given successive washes with 2% NaOH solution and water and

14

then dehydrated under vacuum at about 100° C. The yield, based on POCl_3 , was 90%.

The 2-ethylhexyl dicresyl phosphate which was prepared by the above method had the following properties:

Sp. gr. 25/25° C. 1.064
 Ref. index 25° C. 1.507
 Boiling point at 5 mm. ..... Approx. 243° C.
 Freezing point ..... Below 0° C.
 Color ..... Nearly water white

EXAMPLE X

Iso-octyl dicresyl phosphate

15 153.4 g. of POCl_3 are cooled with stirring to about 10° C. in a glass lined closed reaction vessel. 130.2 g. of iso-octyl alcohol are cooled to about 10° C. and added to the POCl_3 with continuous stirring and cooling and at a rate so as to maintain a reaction temperature of 10 to 15° C. After all of the iso-octyl alcohol has been added to the reaction, the cooling means is removed and while the agitation is continued the reaction temperature is allowed to rise to room temperature.

20 Thereafter, the stirring is continued while the reaction mixture is placed under a vacuum (below 50 mm. Hg) for 1½ hours to complete the reaction and removal of the hydrogen chloride gas which is evolved from the reaction. The product of the above reaction between iso-octyl alcohol and phosphorus oxychloride is iso-octyl phosphoryl dichloride.

An aqueous sodium cresylate solution is prepared by adding 227 g. of cresol to 280 cc. of water having dissolved therein 180.7 g. of 46.5% sodium hydroxide. This sodium cresylate solution is cooled to 0 to 3° C. and the above prepared iso-octyl phosphoryl dichloride is gradually added to the sodium cresylate solution at such a rate as to maintain a reaction temperature below 5° C. After all of the iso-octyl phosphoryl dichloride has been added to the sodium cresylate solution, the temperature is allowed to rise to about 25° C. and the reaction mixture stirred for an additional 3 hours, thereafter the iso-octyl dicresyl phosphate is recovered in the manner as described in the previous example. The yield of iso-octyl dicresyl phosphate, based on POCl_3 , was 89%.

EXAMPLE XI

Nonyl dicresyl phosphate

460.2 g. of POCl_3 are cooled with stirring to a temperature of 5 to 10° C. in a glass lined closed reaction vessel. 432.8 g. of nonyl alcohol (a trimethyl substituted primary hexanol) are cooled to 5 to 10° C. and are added to the POCl_3 with continuous stirring and at a rate so as to maintain a reaction-mass temperature of about 15° C. The reaction mixture is agitated and the temperature of the reaction mixture is allowed to come up to room temperature, thereafter the stirring is continued and the reaction mixture is placed under a vacuum (below 50 mm.) over a period of 2 hours thereby removing the hydrogen chloride gas which is evolved from the reaction.

An aqueous solution of sodium cresylate is prepared by adding 686.7 g. of cresol to 840 cc. of water having dissolved therein 542.0 g. of 46.5% sodium hydroxide. The aqueous sodium cresylate solution is cooled to 0° C. and the nonyl phosphoryl dichloride, prepared by the reaction of the nonyl alcohol and the POCl_3 , is added to the aqueous sodium cresylate solution at such a rate as to maintain a temperature below 5° C. After all of the nonyl phosphoryl dichloride has

been added to the aqueous sodium cresylate solution, the reaction mixture is agitated for a period of 3 hours and allowed to warm up to room temperature. When the agitation is stopped, the reaction mixture separates into an ester layer and an aqueous layer and the ester layer may be then separated from the aqueous layer by decantation. The ester layer is given successive washes with 2% NaOH solution and water and then dehydrated under vacuum at about 100° C. The yield, based on POCl_3 , was 89.7%.

EXAMPLE XII

2-methylpentyl dicresyl phosphate

2-methylpentyl phosphoryl dichloride was prepared by adding 102.1 g. of 2-methylpentanol, cooled to 10° C., to 153.4 g. of phosphorus oxychloride cooled to 10° C. with stirring and cooling and at a rate so as to maintain a reaction temperature of 10 to 15° C. After all of the 2-methylpentanol had been added to the phosphorus oxychloride the reaction was carried to completion to form 2-methylpentyl phosphoryl dichloride in the same manner as was described for the preparation of iso-octyl phosphoryl dichloride.

The 2-methylpentyl phosphoryl dichloride was reacted with an aqueous sodium cresylate solution cooled to 3° C. and prepared by adding 227 g. of cresol to 280 cc. of water having dissolved therein 180.7 g. of 46.5% sodium hydroxide, at such a rate so as to maintain a reaction temperature of 3 to 5° C. After all of the 2-methylpentyl phosphoryl dichloride had been added to the sodium cresylate solution, the cooling means was removed and the reaction temperature allowed to rise to 22° C. Thereafter, the reaction was carried to completion by continuous agitation for about 1½ hours. The 2-methylpentyl dicresyl phosphate was then recovered in the manner described for the preparation of nonyl dicresyl phosphate. The yield of 2-methylpentyl dicresyl phosphate, based on POCl_3 , was 90%.

The 2-methylpentyl dicresyl phosphate prepared as above described had the following properties:

Sp. gr. 25/25° C.	1.081
N_{D}^{25}	1.511
Freezing point	Below 0° C.
Color	Nearly water white

EXAMPLE XIII

2-ethylbutyl dicresyl phosphate

51.1 g. of 2-ethylbutanol were cooled to about 10° C. and slowly added to 76.7 g. of phosphorus oxychloride cooled to 10° C. in a closed glass lined reaction vessel at such a rate as to maintain a reaction temperature of 12 to 14° C. After all of the 2-ethylbutanol had been added to the POCl_3 , the reaction was carried to completion with the formation of 2-ethylbutyl phosphoryl dichloride in the same manner as was described for the preparation of 2-methylpentyl phosphoryl dichloride.

The 2-ethylbutyl phosphoryl dichloride was then added to an aqueous sodium cresylate solution, cooled to 0° C. and prepared by adding 113.4 g. of cresol to 230 g. of 18.2% sodium hydroxide solution. The 2-ethylbutyl phosphoryl dichloride is added to the sodium cresylate solution at such a rate as to maintain a reaction temperature of about 5° C. After all of the 2-ethylbutyl phosphoryl dichloride was added, the reaction was carried to completion, and the ester recov-

ered in the same manner as was described for the preparation of 2-ethylhexyl dicresyl phosphate. The yield of 2-ethylbutyl dicresyl phosphate, based on POCl_3 , was substantially 90%.

EXAMPLE XIV

Dodecyl dicresyl phosphate

118.5 g. of a 12 carbon branched chain primary alcohol prepared from the polymerization products of olefins were cooled with stirring to about 20° C. in a glass lined closed reaction vessel. 97.8 g. of POCl_3 was added, with continuous stirring and cooling, at a rate so as to maintain a reaction temperature of about 20° C. The reaction mixture is agitated and the temperature is slowly raised to 30 to 40° C. and maintained at that temperature for one hour following the addition of all the dodecyl alcohol; thereafter, the temperature is raised to approximately 50° C. and the stirring continued for another hour. The hydrogen chloride gas which is evolved from the reaction is continuously removed by means of applying a vacuum to the reaction vessel.

25 After the reaction between the dodecyl alcohol and the POCl_3 and the removal of the hydrogen chloride have been completed the dodecyl phosphoryl dichloride is transferred to a reactor containing an aqueous sodium cresylate solution, at a temperature below 5° C., prepared from 180 cc. of water, 144.5 g. of cresol and 115.4 g. of 46.5% soda lye. The dodecyl phosphoryl dichloride is added to the sodium cresylate solution at such a rate as to maintain a temperature below 5° C. After all the dodecyl phosphoryl dichloride has been added to the sodium cresylate solution, the reaction mixture is agitated for an hour and then with continuous stirring the temperature is gradually raised to 30° C. The reaction mixture is then allowed to stand until an ester layer and an aqueous layer form and the ester layer is separated from the aqueous layer. The ester is given successive washes with NaOH solution and water and then the ester is dehydrated under vacuum at about 100° C. The yield, based on POCl_3 , was 87.5%.

EXAMPLE XV

2-n-propylheptyl dicresyl phosphate

2-n-propylheptyl phosphoryl dichloride may be prepared by reacting at 15 to 20° C. 158.3 g. of 2-n-propylheptanol with 153.4 g. of POCl_3 in the manner as described for the preparation of the dodecyl phosphoryl dichloride. The 2-n-propylheptyl phosphoryl dichloride is then added to an aqueous solution of sodium cresylate, cooled to 0° C. and prepared by adding 227 g. of cresol to 280 cc. of water having dissolved therein 180.7 g. of 46.5% of soda lye, at a rate so as to maintain a reaction temperature of 0 to 5° C. and carrying the reaction to completion and recovering the ester as described for the preparation of dodecyl dicresyl phosphate. A yield of 2-n-propylheptyl dicresyl phosphate, based on POCl_3 , of substantially 90% may be had.

EXAMPLE XVI

2-methylpentoxymethyl dicresyl phosphate

153.4 g. of POCl_3 were cooled with stirring to about 10° C. in a glass lined closed reaction vessel. 146 g. of ethylene glycol mono-2-methylpentyl ether were cooled to approximately 15° C. and added to the POCl_3 with continuous stirring and at a rate so as to maintain a reaction temperature of 20° C. The reaction mixture is agitated and the reaction temperature of 20° C. is

maintained for one hour following the addition of all the ethylene glycol mono-2-methylpentyl ether, thereafter the temperature is allowed to rise to approximately 25° C. and the stirring continued for another hour. The hydrogen chloride gas which is evolved from the reaction is continuously removed by means of applying a vacuum to the reaction vessel.

After the reaction between the ethylene glycol mono-2-methylpentyl ether and the POCl_3 and the removal of the hydrogen chloride have been completed, the reaction mass containing 2-methylpentoxyethyl phosphoryl dichloride is transferred to a reactor containing 780 g. of an aqueous solution, cooled to about 0° C., having a composition of 35% sodium cresylate. After the 2-methylpentoxyethyl phosphoryl dichloride has been added to the aqueous sodium cresylate solution, the reaction mixture is agitated for an hour and then with continuous stirring the temperature is gradually raised to 30° C. The reaction mixture is then allowed to stand until an ester layer and an aqueous layer form and the ester layer is separated from the aqueous layer. The ester is given successive washes with 2% NaOH solution and water and then dehydrated under vacuum at about 100° C. The yield, based on POCl_3 , was 79%.

EXAMPLE XVII

Butoxyethyl diphenyl phosphate

153.4 g. of POCl_3 are cooled with stirring to about 15° C. in a glass lined closed reaction vessel. 118.1 g. of ethylene glycol monobutyl ether are cooled and added, with stirring, to the POCl_3 over a period of one hour so as to maintain a reaction temperature of about 16° C. The stirring is continued for 1.5 hours after the ethylene glycol monobutyl ether has been added, the temperature being maintained at 15-20° C. and the reaction vessel being held under 50 mm. of vacuum to remove hydrogen chloride gas which is evolved from the reaction. The reaction mixture is substantially butoxyethyl phosphoryl dichloride.

The butoxyethyl phosphoryl dichloride is added to a sodium phenate solution consisting of 243.6 g. of sodium phenate and 450 cc. of water over a period of 2½ hours while maintaining a reaction temperature of 0-3° C. Thereafter the temperature is allowed to rise to 20° C. and the stirring continued for about two additional hours. The reaction mixture is then allowed to stand until an ester layer and an aqueous layer form and the ester layer is then separated from the aqueous layer. The ester is given successive washes with 2% NaOH solution and water and then dehydrated under vacuum at about 100° C. The yield, based on POCl_3 , was 89%.

The butoxyethyl diphenyl phosphate which was prepared in the above manner had the following properties:

Sp. gr. 25/25° C.	1.146
N_{D}^{25}	1.511
Freezing point	Below 0° C.
Color	Essentially colorless

EXAMPLE XVIII

2-ethylhexoxyethyl diphenyl phosphate

174 g. of ethylene glycol mono 2-ethylhexyl ether cooled to about 15° C. were slowly added with stirring to 153.4 g. of POCl_3 , previously cooled to 15° C. and contained in a closed glass lined reaction vessel, at such a rate so as to maintain

a reaction temperature of 15 to 18° C. with continuous cooling of the reaction vessel. The reaction mixture is agitated for one hour following the addition of the ethylene glycol mono-2-ethylhexyl ether while maintaining a reaction temperature of 18 to 20° C., thereafter the temperature is allowed to rise to 25° C. and the stirring continued for another 1½ hours while a vacuum of 50 mm. Hg. is applied to the reaction vessel to remove the hydrogen chloride gas which is evolved from the reaction. The reaction product is 2-ethylhexoxyethyl phosphoryl dichloride.

The 2-ethylhexoxyethyl phosphoryl dichloride was added with stirring to about 695 g. of a 35% sodium phenate solution cooled to 0-3° C. The reaction mixture is continuously cooled and the 2-ethylhexoxyethyl phosphoryl dichloride is added at a rate so as to maintain a reaction temperature of 0 to 5° C., which can be accomplished in 2½ to 3 hours. Thereafter, the reaction temperature is allowed to rise to room temperature and the stirring continued for an additional 2 hours to finish off the reaction. The reaction mixture is then allowed to stand until an ester layer of 2-ethylhexoxyethyl diphenyl phosphate separates from the aqueous layer and the ester is then separated from the aqueous layer by decantation. The ester is given successive washes with 2% NaOH solution and water and then dehydrated under vacuum at about 100° C. The yield, based on POCl_3 , was 84%.

EXAMPLE XIX

2-ethylhexoxyethyl dicresyl phosphate

2-ethylhexoxyethyl phosphoryl dichloride was prepared in the manner as was described for the preparation of 2-ethylhexoxyethyl diphenyl phosphate.

690 g. of a sodium cresylate solution was prepared by adding 227 g. of m-cresol to about 463 g. of an aqueous sodium hydroxide solution containing 84 g. of NaOH, cooled to about 3° C., and while the cooling was continued, the 2-ethylhexoxyethyl phosphoryl dichloride was added to the sodium cresylate solution with stirring and at such a rate as to maintain a reaction temperature of 0 to 5° C. The temperature of the reaction mass was then allowed to rise to room temperature while the stirring was continued and the reaction was completed in about two hours. The 2-ethylhexoxyethyl dicresyl phosphate, recovered in the manner as described for 2-ethylhexoxyethyl diphenyl phosphate, was obtained in a yield of 89%, based on POCl_3 .

EXAMPLE XX

2-n-propylheptoxyethyl dicresyl phosphate

76.7 g. of phosphorus oxychloride were cooled to 15° C. in a glass lined closed reaction vessel, and with continuous cooling of the reactor, 101 g. of ethylene glycol mono-2-n-propylheptyl ether were added with stirring to the phosphorus oxychloride at a rate so as to maintain a reaction temperature of 15 to 20° C. After all of the ethylene glycol mono-2-n-propylheptyl ether had been added, the agitation was continued while the temperature was raised to about 25° C., at which time a vacuum of 25 mm. Hg was applied to the reactor and maintained for about two hours to remove the hydrogen chloride evolved and carry the reaction to completion to form 2-n-propylheptoxyethyl phosphoryl dichloride.

An aqueous solution of sodium cresylate, prepared by adding 113.5 g. of cresol to an aqueous

alkaline solution prepared by dissolving 89.6 g. of 46.5% soda lye in 140 cc. of water is cooled to 0° C. and the 2-n-propylheptoxyethyl phosphoryl dichloride is added to the cooled sodium cresylate solution with stirring and at a rate so as to maintain a reaction temperature of about 5° C. Thereafter, the reaction is finished off by slowly raising the temperature to about 25° C. and stirring for 2½ to 3 hours. The finished ester is then recovered in the manner described for the preparation of 2-ethylhexoxyethyl diresyl phosphate. The yield of 2-n-propylheptoxyethyl diresyl phosphate was 90%.

EXAMPLE XXI

Dodecoxyethyl diphenyl phosphate

To 200 g. of POCl_3 , cooled to about 20° C. in a closed and continuously cooled reactor, 300 g. of ethylene glycol monododecyl ether were added, with stirring and at a rate so as to maintain a reaction temperature of about 20° C. After all of the ethylene glycol monododecyl ether had been added to the POCl_3 , the reaction mixture was agitated and the temperature slowly raised to and maintained at 30° to 40° C. for about one hour. Thereafter the temperature was raised to 50° C. and maintained at that temperature for an additional hour while the stirring was continued and a vacuum of 25 mm. Hg was applied to the reactor to remove the hydrogen chloride formed during the reaction. The product of this reaction was dodecoxyethyl phosphoryl dichloride.

A sodium phenate solution, prepared by reacting 257.5 g. of phenol with 650 g. of an aqueous caustic solution containing 109.3 g. of NaOH, was cooled to 5° C. and while the cooling of the sodium phenate solution was continued, the above prepared dodecoxyethyl phosphoryl dichloride was slowly added to the cooled sodium phenate solution with stirring and at a rate so as to maintain a reaction temperature of about 5° C. Thereafter, the temperature was slowly raised to 30° C. and the stirring continued for another hour, at which time the reaction was finished with the formation of dodecoxyethyl diphenyl phosphate. When the stirring of the reaction mixture is stopped, the mixture separates into an aqueous layer and an ester layer. The ester was given successive washes with 2% NaOH solution and water and then dehydrated under vacuum at about 100° C. The yield of dodecoxyethyl diphenyl phosphate, based on POCl_3 , was 84%.

EXAMPLE XXII

Butoxyethyl di (o-chlorophenyl) phosphate

153.4 g. (1.0 mol) of POCl_3 are cooled with stirring to about 15° C. in a glass lined closed reaction vessel. 118 g. (1.0 mol) of anhydrous ethylene glycol monobutyl ether which has been cooled to approximately 15° C. is added to the POCl_3 with continuous stirring and at a rate so as to maintain a reaction temperature of about 15° C. The reaction mixture is agitated and by means of continuous stirring the reaction temperature of 15° C. is maintained for one hour following the addition of all of the ethylene glycol monobutyl ether, thereafter the temperature is allowed to rise to 25° C. and the stirring continued for another hour while the hydrogen chloride gas which is evolved from the reaction is continuously removed by means of applying a vacuum of 25 mm. Hg to the reaction vessel. The reaction product is butoxyethyl phosphoryl dichloride.

A sodium o-chlorophenate was prepared by adding 282.3 g. (2.1 mols) of o-chlorophenol (95.6%) to an aqueous alkaline solution prepared by dissolving 175.6 g. of 48% sodium hydroxide in 280 cc. of water. This solution of sodium o-chlorophenate is cooled to 3° C. and with continuous cooling 230.7 g. of the butoxyethyl phosphoryl dichloride are added to the sodium o-chlorophenate solution at such a rate as to maintain a reaction temperature below 5° C. After all of the butoxyethyl phosphoryl dichloride has been added to the sodium o-chlorophenate solution, the reaction mixture is agitated for an additional hour and then, with continuous stirring, allowed to warm up to room temperature. The mixture is then allowed to stand until an ester layer of butoxyethyl di (o-chlorophenyl) phosphate and an aqueous layer form and the ester layer is then separated from the aqueous layer by decantation. The ester is given successive washes with 2% sodium hydroxide solution and water and then dehydrated under vacuum at about 100° C. The yield, based on POCl_3 , was 80.7%.

The butoxyethyl di (o-chlorophenyl) phosphate prepared in the above manner had the following properties:

Sp. gr. 25/25° C	-----	1.257
N_D^{25}	-----	1.525

EXAMPLE XXIII

2-ethylhexyl di (o-chlorophenyl) phosphate

130.2 g. of 2-ethylhexanol were cooled with stirring to about 10° C. and added to 153.4 g. of POCl_3 which were cooled to approximately 10° C. in a glass lined reactor with continuous stirring and at a rate so as to maintain a reaction temperature of 10°-15° C. The reaction mixture was agitated and the temperature was slowly raised to 25° C. and maintained at that temperature for one hour following the addition of all the 2-ethylhexanol; thereafter the temperature was raised to approximately 30° C. and the stirring continued for another hour while the remaining hydrogen chloride gas which was evolved from the reaction was removed by means of applying a vacuum of 75 mm. Hg to the reaction vessel. The product of the above reaction was 2-ethylhexyl phosphoryl dichloride.

168.6 g. of 49.8% sodium hydroxide solution were added to a mixture of 284.4 g. (2.1 mols) of 95.6% o-chlorophenol and 280 cc. of water to form an aqueous solution of sodium o-chlorophenate. This solution was stirred and cooled to about 5° C. and while the cooling and stirring was continued, the above prepared 2-ethylhexyl phosphoryl dichloride was slowly added to the cooled solution of sodium o-chlorophenate at a rate so that the reaction temperature below 5° C. could be maintained. After all the 2-ethylhexyl phosphoryl dichloride has been added to the sodium chlorophenate solution, the reaction mixture is agitated for an hour and then with continuous stirring the temperature is gradually raised to 30° C. The reaction mixture is then allowed to stand until an ester layer and an aqueous layer form and the ester layer is separated from the aqueous layer by decantation. The ester is given successive washes with 2% NaOH solution and water and then dehydrated under vacuum at about 100° C. The yield of 2-ethylhexyl di (o-chlorophenyl) phosphate, based on POCl_3 , was 88%.

21

EXAMPLE XXIV

Tridecyl diphenyl phosphate

120.1 g. of a 13 carbon branched chain primary alcohol prepared from the polymerization products of olefins were cooled to about 20° C. and added to 92.0 g. of POCl_3 cooled to about 20° C. in a glass lined closed reaction vessel with continuous stirring and cooling so as to maintain a reaction temperature of about 20° C. The reaction mixture was agitated and the temperature slowly raised to 30° to 40° C. and maintained at that temperature for one hour following the addition of all the tridecyl alcohol. The temperature was then raised to about 50° C. and the stirring continued for another hour. The hydrogen chloride gas which was evolved from the reaction was continuously removed by means of applying a vacuum to the reaction vessel.

158.9 g. of the above prepared tridecyl phosphoryl dichloride were transferred to a reactor containing about 325 g. of an aqueous sodium phenate solution, at a temperature below 15° C., prepared from 140 cc. of water, 98.8 g. of phenol, and 87.0 g. of 48.3% sodium hydroxide. The tridecyl phosphoryl dichloride was added to the sodium phenate solution at such a rate as to maintain a temperature between 11° and 14° C. After all the tridecyl phosphoryl dichloride had been added to the sodium phenate solution, the reaction was carried to completion. The reaction mixture was then allowed to stand until an ester layer and an aqueous layer formed and the ester layer was separated from the aqueous layer. The ester was given successive washes with NaOH solution and water and then dehydrated under vacuum at 100° C. The yield, based on POCl_3 , was 88.8%.

The tridecyl diphenyl phosphate prepared in the above manner, had the following properties:

Sp. gr. 25/25° C.....	1.0440
N_D^{25}	1.5014
Pour point.....	-45° F.
Color.....	Nearly water white
Viscosity at 100° F.....	97.37 Universal Saybolt seconds
Viscosity at 210° F.....	38.77 Universal Saybolt seconds

EXAMPLE XXV

Tetradecyl diphenyl phosphate

76.7 g. of POCl_3 were cooled with stirring to a temperature of 5° to 10° C. in a glass lined closed reaction vessel. 107.1 g. of a 14 carbon branched chain primary alcohol prepared from the polymerization products of olefins were cooled to 5° to 10° C. and added to the POCl_3 with continuous stirring at a rate so as to maintain a reaction mass temperature of about 15° C. The reaction mixture was agitated and the temperature of the reaction mixture allowed to come up to room temperature, thereafter the stirring was continued and the reaction mixture placed under vacuum (below 50 mm.) over a period of 2 hours thereby removing the hydrogen chloride gas which was evolved during the reaction.

An aqueous solution of sodium phenate was prepared by adding 79.0 g. of phenol to 130 cc. of water having dissolved therein 69.7 g. of 48.3% sodium hydroxide. The aqueous sodium phenate solution was cooled to about 5° C. and 132.5 g. of the above prepared tetradecyl phosphoryl dichloride was added to the aqueous sodium phenate

22

solution over a period of about two hours and at such a rate as to maintain a temperature between 5° C. and 15° C. After all of the tetradecyl phosphoryl dichloride was added the reaction was taken to completion and then allowed to stand and separate into an ester layer and an aqueous layer. The ester layer was removed and given successive washes with a 2% NaOH solution and water and then dehydrated under vacuum at about 100° C. The yield, based on POCl_3 , was 87.1%.

The tetradecyl diphenyl phosphate prepared as above described had the following properties:

Sp. gr. 25/25° C.....	1.0382
N_D^{25}	1.5007
Pour point.....	-40° F.
Color.....	Nearly water white
Viscosity at 100° F.....	106.82 Universal Saybolt seconds
Viscosity at 210° F.....	39.31 Universal Saybolt seconds

EXAMPLE XXVI

Octadecyl diphenyl phosphate

The octadecyl alcohol used in this example was 2-(1,3,3-trimethylbutyl)-5,7,7-trimethyl-1-octanol prepared from the polymerization products of olefins.

76.7 g. of POCl_3 were cooled with stirring to about 25° C. in a glass lined closed reaction vessel. 135.5 g. of the above described octadecyl alcohol were cooled and added to the POCl_3 at a rate so as to maintain a reaction temperature of about 25° C. The reaction mixture was continuously agitated and the temperature allowed to rise to room temperature and maintained at this temperature for an additional one hour stirring period during which time the hydrogen chloride gas evolved during the reaction was removed by means of applying a vacuum (below 30 mm. Hg) to the reaction vessel.

The octadecyl phosphoryl dichloride was then transferred to a reactor containing an aqueous sodium phenate solution cooled to 25° C. and prepared by adding 98.7 g. of phenol to 139 cc. of water having dissolved therein 90.5 g. of 46.5% sodium hydroxide. The octadecyl phosphoryl dichloride was added to the aqueous sodium phenate solution at such a rate as to maintain a temperature below 30° C. After all the octadecyl phosphoryl dichloride was added the reaction mixture was stirred for an additional three hours allowing the mixture to come to room temperature. On standing the reaction mixture separated into an aqueous layer and an ester layer. The ester layer was removed and given successive washes with 2% NaOH solution and water and finally dehydrated under vacuum at about 110° C. The yield of octadecyl diphenyl phosphate, based on POCl_3 , was about 87%.

EXAMPLE XXVII

n-Hexyl diphenyl phosphate

153.4 g. of POCl_3 are cooled with stirring to about 5° C. in a glass lined closed reaction vessel. 102.1 g. of n-hexyl alcohol are cooled to about 10° C. and added to the POCl_3 with continuous stirring and at a rate so as to maintain a reaction temperature of about 10° C. The reaction mixture is continuously agitated over a period of about 1 hour. The mixture is then stirred for an additional hour under vacuum (below 30 mm.)

23

to remove the hydrogen chloride gas which is evolved.

An aqueous sodium phenate solution is prepared by adding 158.0 g. of phenol to 200 cc. of water having dissolved therein 139.0 g. of 48.3% sodium hydroxide. The sodium phenate solution is cooled to about 5° C. and 175.4 g. of the hexyl phosphoryl dichloride previously prepared is gradually added to the sodium phenate solution maintaining a temperature below 10° C. After all the hexyl phosphoryl dichloride has been added, the temperature is allowed to rise to about 25° C. and the reaction mixture stirred for an additional 5 hours. When the agitation is stopped, the mixture separates into an ester layer and an aqueous layer. The ester layer is recovered and given successive washes with a 2% sodium hydroxide solution and water and then further refined in accordance with the usual methods well known to those skilled in the art of refining phosphate esters. The yield, based on POCl_3 , was 87.2%.

The n-hexyl diphenyl phosphate prepared as above described had the following properties:

Color	Nearly water white
Sp. gr. 25/25° C.	1.1172
N_D^{25}	1.5062

EXAMPLE XXVIII

n-Octyl diphenyl phosphate

This ester was prepared by first reacting 195.2 g. of n-octyl alcohol with 230.1 g. of POCl_3 , in the manner as described for the preparation of 2-ethylhexyl phosphoryl dichloride, to form n-octyl phosphoryl dichloride.

246.0 g. of the above prepared n-octyl phosphoryl dichloride was then slowly added to an aqueous sodium phenate solution which had been prepared by dissolving 192.8 g. of phenol in 280 cc. of water, having dissolved therein 170.0 g. of 48.3% soda lye. This addition procedure was carried out at such a rate so as to maintain a reaction temperature below 20° C. After all of the n-octyl phosphoryl dichloride had been added, the reaction mixture was stirred for an additional 3½ hours while allowing the temperature of the mixture to rise to room temperature. The ester was then separated from the reaction mixture and purified in the same manner as was described in the preparation of 2-ethylhexyl diphenyl phosphate. The yield of n-octyl diphenyl phosphate, based on POCl_3 , was 89.5%.

The n-octyl diphenyl phosphate prepared as described above had the following properties:

Color	Nearly water white
Sp. gr. 25/25° C.	1.0843
N_D^{25}	1.5062

EXAMPLE XXIX

n-Decyl diphenyl phosphate

158.1 g. of n-decyl alcohol were cooled to about 20° C. and added to 153.4 g. of POCl_3 cooled to approximately 20° C. in a glass lined closed reaction vessel with continuous stirring and cooling so as to maintain a reaction temperature of about 20° C. After all of the n-decyl alcohol had been added, while continuously agitating the mixture for an additional hour the temperature was slowly raised to about 50° C. and a vacuum applied to the system to remove the hydrogen chloride gas evolved from the reaction.

After the reaction between the n-decyl alcohol and POCl_3 had been completed, the reaction mix-

24

ture containing n-decyl phosphoryl dichloride was transferred to reactor containing about 197 g of phenol, 172 g. of 50% sodium hydroxide and 300 cc. of water at a temperature below 5° C. The n-decyl phosphoryl dichloride was added at such a rate so as to maintain a reaction temperature below 5° C. After the addition had been completed, the reaction mixture was allowed to rise to room temperature with continuous stirring for an additional 2½ hours. The mixture was then allowed to stand whereupon it separated into an aqueous layer and an ester layer which was recovered, given successive washes with a sodium hydroxide solution and water and then further refined in accordance with the usual methods well known to those skilled in the art. The yield based on POCl_3 , is 81.5%.

The n-decyl diphenyl phosphate prepared as herein described had the following properties:

Color	Nearly water white
N_D^{25}	1.5025
Sp. gr. 25/25° C.	1.0627

EXAMPLE XXX

Lauryl diphenyl phosphate

Lauryl phosphoryl dichloride was prepared in the manner described for the preparation of n-decyl phosphoryl dichloride by reacting 139.5 g of lauryl alcohol with 115.1 g. of POCl_3 while maintaining a reaction temperature of about 25° C. The lauryl phosphoryl dichloride thus obtained was added over a period of 1½ hours and at such a rate so as to maintain a temperature of about 25° C., to an aqueous sodium phenate solution which had been prepared by dissolving 150.6 g. of phenol in 230 cc. of water having dissolved therein 128.0 g. of 50% sodium hydroxide. After all of the lauryl phosphoryl dichloride had been added, the reaction mixture was stirred for an additional 3 hours. The mixture was then allowed to stand whereupon it separated into an aqueous layer and an ester layer. The ester layer was recovered, given successive washes with a sodium hydroxide solution and water to remove any partial esters and unreacted phenol, and then dehydrated under vacuum at about 110° C. The yield based upon POCl_3 was about 87%. The lauryl diphenyl phosphate prepared according to the above procedure had the following properties:

Color	Nearly water white
Sp. gr. 25/25° C.	1.0382
N_D^{25}	1.4979

EXAMPLE XXXI

n-Hexadecyl diphenyl phosphate

153.4 g. of POCl_3 are cooled with stirring to about 15° C. in a glass lined closed reaction vessel. 242.4 g. of n-hexadecyl alcohol are heated to about 50° to 60° C. and added to the POCl_3 with continuous stirring over a period of about 1½ hours and at such a rate so as to maintain a reaction temperature of from 10° to 15° C. The reaction mass is then slowly heated to 26° C. and stirred for an additional hour while removing under vacuum the hydrogen chloride gas which is evolved. The reaction mixture now contains predominantly n-hexadecyl phosphoryl dichloride.

An aqueous sodium phenate solution is prepared by adding 197.5 g. of phenol to 280 cc. of water having dissolved therein 178.7 g. of 47% sodium hydroxide. The n-hexadecyl phosphoryl dichloride is slowly added to the sodium phenate solution over a period of about 1 hour while main-

taining a reaction temperature of about 25° C. After all of the reactant has been added, the reaction mixture is stirred for an additional 3 hours after which time the mixture is allowed to stand whereupon it separates into an ester layer and an aqueous layer. The ester layer is separated from the aqueous layer by decantation, given successive washes with 2% sodium hydroxide solution and water and then dehydrated under vacuum at about 105° C. The yield of n-hexadecyl diphenyl phosphate, based on POCl_3 , is 79.3%.

The n-hexadecyl diphenyl phosphate prepared as herein described had the following properties:

Color ----- Nearly water white
 N_D^{25} ----- 1.4934
 Sp. gr. 25/25° C. ----- 1.0122
 Crystallizing point ----- +13.7° C.

EXAMPLE XXXII

n-Octadecyl diphenyl phosphate

153.4 g. of POCl_3 are cooled with stirring to about 10° C. in a glass lined closed reaction vessel. 270 g. of powdered n-octadecyl alcohol are added to the POCl_3 with continuous stirring and at a rate so as to maintain a reaction temperature of about 25° C. The reaction mixture is continuously agitated over a period of about 1 hour. While the stirring is continued, the temperature is slowly raised to about 40° C. and the reaction mixture placed under a vacuum (below 50 mm.) for another 1½ hours to remove the hydrogen chloride gas which is evolved from the reaction. The reaction mixture now contains predominantly n-octadecyl phosphoryl dichloride.

An aqueous sodium phenate solution is prepared by adding 197 g. of phenol to 300 cc. of water having dissolved therein 181 g. of 46.5% soda lye. The n-octadecyl phosphoryl dichloride is gradually added to the sodium phenate solution at such a rate as to maintain a temperature of about 30° C. After all of the reactant has been added, the temperature is raised to about 40° C. and the reaction mixture stirred for an additional 2 hours. When the agitation is stopped, the reaction mixture separates into an ester layer and an aqueous layer and the ester layer is then separated from the aqueous layer by decantation. The ester layer is given successive washes with 2% sodium hydroxide solution and water and then dehydrated under vacuum at about 100° C. thereby obtaining substantially pure n-octadecyl diphenyl phosphate.

EXAMPLE XXXIII

n-Tetradecoxethyl dicresyl phosphate

153.4 g. of POCl_3 are cooled with stirring to about 10° C. in a glass lined closed reaction vessel. 258 g. of ethylene glycol mono-n-tetradecyl ether are cooled to approximately 15° C. and added to the POCl_3 with continuous stirring and at a rate so as to maintain a reaction temperature of 20° C. The reaction mixture is agitated and the reaction temperature of 20° C. maintained for 1 hour following the addition of all the reactant, thereafter the temperature is allowed to rise to about 25° C. and the stirring continued for another hour. The hydrogen chloride gas which is evolved from the reaction is continuously removed by means of applying a vacuum to the reaction vessel.

The tetradecoxethyl phosphoryl dichloride is transferred to a reactor containing 780 g. of an aqueous solution, cooled to about 0° C., having a composition of 35% sodium cresylate. After

all of the reactant has been added to the aqueous sodium cresylate solution, the reaction mixture is agitated for 1½ hours and then with continuous stirring the temperature is gradually raised to 30° C. The reaction mixture is then allowed to stand until an ester layer and an aqueous layer form, and the ester layer is separated from the aqueous layer. The ester is given successive washes with a sodium hydroxide solution and water and then dehydrated under vacuum at about 110° C. thereby obtaining n-tetradecoxethyl dicresyl phosphate.

What is claimed is:

1. In a process for the preparation of mono-alkyl diaryl phosphate esters of the type

wherein R_1 represents a radical selected from the group consisting of alkyl radicals terminating with a CH_2 group and containing at least 6 and not more than 18 carbon atoms and beta-alkoxyethyl radicals wherein the alkyl substituent contains at least 4 and not more than 18 carbon atoms and R_2 is selected from the group consisting of phenyl, cresyl and chlorophenyl radicals, the steps comprising reacting a one molecular proportion of a primary aliphatic alcohol selected from the group consisting of primary alkyl alcohols wherein the alkyl radical contains at least 6 and not more than 18 carbon atoms and beta-alkoxyethyl alcohols wherein the alkyl substituent contains at least 4 and not more than 18 carbon atoms with a substantially one molecular proportion of phosphorus oxychloride while maintaining a reaction temperature between about +2° C. and about +25° C. until the reaction between the selected aliphatic alcohol and the phosphorus oxychloride is substantially complete and while removing the hydrogen chloride formed and thereafter continuing the removal of hydrogen chloride formed at a temperature not exceeding 50° C., to form a monoalkyl phosphoryl dichloride and adding said monoalkyl phosphoryl dichloride to substantially two molecular proportions of a sodium arylate in an aqueous solution while maintaining a reaction temperature of -10° C. to +50° C., said sodium arylate being selected from the group consisting of sodium phenate, sodium cresylate, and sodium chlorophenate.

2. In a process for the preparation of mono-alkyl diaryl phosphate esters of the type

wherein R_1 represents a radical selected from the group consisting of alkyl radicals terminating with a CH_2 group and containing at least 6 and not more than 18 carbon atoms and beta-alkoxyethyl radicals wherein the alkyl substituent contains at least 4 and not more than 18 carbon atoms and R_2 is selected from the group consisting of phenyl, cresyl and chlorophenyl radicals, the steps comprising reacting a one molecular proportion of a primary aliphatic alcohol selected from the group consisting of primary alkyl alcohols wherein the alkyl radical contains at least 6 and not more than 18 carbon atoms and beta-alkoxyethyl alcohols wherein the alkyl substituent contains at least 4 and not more than 18 carbon atoms with a substantially one molecular proportion of phosphorus oxychloride while maintaining a reaction temperature between about +2° C. and about +25° C. until the reaction between the selected aliphatic alcohol

and the phosphorus oxychloride is substantially complete and while removing the hydrogen chloride formed and thereafter continuing the removal of the hydrogen chloride formed under a reduced pressure and at a temperature not exceeding 50° C., to form a monoalkyl phosphoryl dichloride and adding said monoalkyl phosphoryl dichloride to substantially two molecular proportions of a sodium arylate in an aqueous solution while maintaining a reaction temperature of -10° C. to +50° C., said sodium arylate being selected from the group consisting of sodium phenate, sodium cresylate, and sodium chlorophenate.

3. The process for the preparation of mono- 18 alkyl diaryl phosphate esters of the type

wherein R₁ represents a radical selected from the group consisting of alkyl radicals terminating with a CH₃ group and containing at least 6 and not more than 18 carbon atoms and beta-alkoxyethyl radicals wherein the alkyl substituent contains at least 4 and not more than 18 carbon atoms and R₂ is selected from the group consisting of phenyl, cresyl and chlorophenyl radicals, comprising reacting a one molecular proportion of a primary aliphatic alcohol selected from the group consisting of primary alkyl alcohols wherein the alkyl radical contains at least 6 and not more than 18 carbon atoms and beta-alkoxyethyl alcohols wherein the alkyl substituent contains at least 4 and not more than 18 carbon atoms with a substantially one molecular proportion of phosphorus oxychloride while maintaining a reaction temperature between +2° C. and +25° C. and while removing the hydrogen chloride formed, to form a monoalkyl phosphoryl dichloride and adding said monoalkyl phosphoryl dichloride to substantially two molecular proportions of a sodium arylate in an aqueous solution while maintaining a reaction temperature of -10° C. to +50° C., said sodium arylate being selected from the group consisting of sodium phenate, sodium cresylate, and sodium chlorophenate, and recovering the substantially pure monoalkyl diaryl ester of ortho-phosphoric acid.

4. The process for the preparation of monoalkyl diaryl phosphate esters of the type

wherein R₁ represents a radical selected from the group consisting of alkyl radicals terminating with a CH₃ group and containing at least 6 and not more than 18 carbon atoms and beta-alkoxyethyl radicals wherein the alkyl substituent contains at least 4 and not more than 18 carbon atoms and R₂ is selected from the group consisting of phenyl, cresyl, and chlorophenyl radicals, comprising reacting a one molecular proportion of a primary aliphatic alcohol selected from the group consisting of primary alkyl alcohols wherein the alkyl radical contains at least 6 and not more than 18 carbon atoms and beta-alkoxyethyl alcohols wherein the alkyl substituent contains at least 4 and not more than 18 carbon atoms with a substantially one molecular proportion of phosphorus oxychloride while maintaining a reaction temperature between +2° C. and +25° C. and while removing under reduced pressure the hydrogen chloride formed, to form a monoalkyl phosphoryl dichloride and adding said monoalkyl phosphoryl dichloride to substantially two molec-

ular proportions of a sodium arylate in an aqueous solution while maintaining a reaction temperature of -10° C. to +50° C., said sodium arylate being selected from the group consisting of sodium phenate, sodium cresylate, and sodium chlorophenate, and recovering the substantially pure monoalkyl diaryl ester of ortho-phosphoric acid.

5. In a process for the preparation of mono- 10 alkyl diaryl phosphate esters of the type

wherein R₁ represents a radical selected from the group consisting of alkyl radicals terminating with a CH₃ group and containing at least 6 and not more than 18 carbon atoms and beta-alkoxyethyl radicals wherein the alkyl substituent contains at least 4 and not more than 18 carbon atoms and R₂ is selected from the group consisting of phenyl, cresyl and chlorophenyl radicals, the steps comprising reacting a one molecular proportion of a primary aliphatic alcohol selected from the group consisting of primary alkyl alcohols wherein the alkyl radical contains at least 6 and not more than 18 carbon atoms and beta-alkoxyethyl alcohols wherein the alkyl substituent contains at least 4 and not more than 18 carbon atoms with a substantially one molecular proportion of phosphorus oxychloride while maintaining a reaction temperature between +2° C. and +25° C. and while removing under reduced pressure the hydrogen chloride formed, thereby forming a substantially pure monoalkyl phosphoryl dichloride, and adding the said monoalkyl phosphoryl dichloride to a substantially two molecular proportion of a sodium arylate in an aqueous solution while maintaining a reaction temperature of 0° C. to 25° C., said sodium arylate being selected from the group consisting of the sodium salts of phenol, cresol, and chlorophenol.

6. In a process for the preparation of monoalkyl diaryl phosphate esters of the type

wherein R₁ represents a branched chain alkyl radical containing at least 5 and not more than 17 carbon atoms and R₂ is selected from the group consisting of phenyl, cresyl, and chlorophenyl radicals, the steps comprising reacting a one molecular proportion of a primary branched chain alkyl alcohol containing at least 6 and not more than 18 carbon atoms with a substantially one molecular proportion of phosphorus oxychloride while maintaining a reaction temperature between +2° C. and +25° C. and while removing under reduced pressure the hydrogen chloride formed, thereby forming a substantially pure monoalkyl phosphoryl dichloride, adding the said monoalkyl phosphoryl dichloride to a substantially two molecular proportion of a sodium arylate in an aqueous solution while maintaining a reaction temperature of 0° C. to 25° C., said sodium arylate being selected from the group consisting of the sodium salts of phenol, cresol, and chlorophenol.

7. In a process for the preparation of mono- 70 alkyl diaryl phosphate esters of the type

wherein R₁ represents a branched chain alkyl radical containing at least 5 and not more than 11 carbon atoms and R₂ is selected from the

29

group consisting of phenyl, cresyl, and chlorophenyl radicals, the steps comprising reacting a one molecular proportion of a primary, branched chain, alkyl alcohol containing at least 6 and not more than 12 carbon atoms with a substantially one molecular proportion of phosphorus oxychloride while maintaining a reaction temperature between +2° C. and +25° C. and while removing under reduced pressure the hydrogen chloride formed, thereby forming a substantially pure monoalkyl phosphoryl dichloride, adding the said monoalkyl phosphoryl dichloride to a substantially two molecular proportion of a sodium arylate in an aqueous solution while maintaining a reaction temperature of 0° C. to 25° C., said sodium arylate being selected from the group consisting of the sodium salts of phenol, cresol, and chlorophenol.

8. In a process for the preparation of monoalkyl diaryl phosphate esters of the type

wherein R_1 represents a branched chain alkyl radical containing at least 5 and not more than 11 carbon atoms and R_2 is selected from the group consisting of phenyl, cresyl, and chlorophenyl radicals, the steps comprising reacting a one molecular proportion of a primary, branched chain, alkyl alcohol containing at least 6 and not more than 12 carbon atoms with a substantially one molecular proportion of phosphorus oxychloride while maintaining a reaction temperature between +2° C. and +25° C. and while removing the hydrogen chloride formed, thereby forming a substantially pure monoalkyl phosphoryl dichloride, adding the said monoalkyl phosphoryl dichloride to a substantially two molecular proportion of a sodium arylate in an aqueous solution while maintaining a reaction temperature of 0° C. to 25° C., said sodium arylate being selected from the group consisting of the sodium salts of phenol, cresol, and chlorophenol.

9. The process described in claim 8, wherein the alkyl alcohol is a primary branched chain alkyl alcohol containing eight carbon atoms.

10. The process as described in claim 8, wherein the alkyl alcohol is 2-ethylhexanol and the sodium arylate is sodium phenate.

11. The process as described in claim 8, wherein

30

the alkyl alcohol is 2-ethylhexanol and the sodium arylate is sodium para-cresylate.

12. The process as described in claim 8, wherein the alkyl alcohol is iso-octanol and the sodium arylate is sodium phenate.

13. The process for the preparation of monoalkyl diaryl phosphate esters of the type

wherein R_1 represents an alkyl radical containing at least 5 and not more than 17 carbon atoms and R_2 is selected from the group consisting of phenyl, cresyl, and chlorophenyl radicals, comprising reacting a one molecular proportion of a primary alkyl alcohol containing at least 6 and not more than 18 carbon atoms with a substantially one molecular proportion of phosphorus oxychloride while maintaining a reaction temperature between +2° C. and +25° C., and while removing under reduced pressure the hydrogen chloride formed, thereby forming a substantially pure monoalkyl phosphoryl dichloride, adding the said monoalkyl phosphoryl dichloride to a substantially two molecular proportion of a sodium arylate in an aqueous solution while maintaining a reaction temperature of 0° C. to 25° C., said sodium arylate being selected from the group consisting of the sodium salts of phenol, cresol, and chlorophenol, and separating the monoalkyl diaryl phosphate ester and washing said ester alternately with water and a dilute alkaline solution and subsequently drying said ester under vacuum at substantially 100° C.
